MEANS FOR PREVENTING CROSS TALK IN
SOUND-VISION SYSTEMSKurt Schlesinger, New York, N. Y., assignor to
Radio Corporation of America, a corporation
of Delaware

Application April 20, 1945, Serial No. 589,338

17 Claims. (Cl. 178—5.8)

1

This invention is directed to signalling systems and particularly to new and improved television methods and means whereby signals representative of both the image and the accompanying or related sound or any other intelligence effects may be transmitted over a common carrier by suitable diplexing or multiplexing in such a way that the effect on the observer of the finally reproduced signals shall be as if the independent series of signalling indications were each continuous.

It has already been proposed in the art to transmit signalling indications of both the sight (video) and the sound (audio) effects by what are known as video modulation signals and audio modulation signals, and various ways and means to accomplish such results have already been set forth.

In these systems of the prior art, it has been customary, where a signal carrier is utilized to radiate signals representative of the sight and the sound, to provide an arrangement whereby the image or video signals modulate the carrier in substantially the usual manner; this modulation is then usually followed by way of the desired control signal, such as sync and/or related or image control signals, and suitable modulation representative of the audio or sound effects. The audio effects in the transmission are produced by virtue of a varying duration signal as might result from scanning a variable width or area sound recording on the edge of a motion picture film, for instance, with the scanning direction being transverse to the film, or the signals may result from scanning a variable density sound record on the edge of the motion picture film, with the scanning direction also being transverse to the film. The Wald Reissue Patent No. 22,025 is illustrative of a system of this character.

Further than this, it has already been proposed to provide transmission of video modulations and audio modulations in such a manner that the two series of signals are alternately transmitted and used to modulate a single carrier. In such systems the audio modulation signals are frequently substantially of the type which are known in the art as the constant frequency variable duration type.

Signals of this general type used to modulate a carrier to convey sound intelligence have already been suggested in the art by Kell in U. S. Patent No. 2,061,734, granted November 24, 1936. Signals of the type where the video and the audio modulations follow one another, and where the audio modulation signal is of variable duration have already been represented in the art

5 by Roosenstein in U. S. Patent No. 2,227,108, granted December 31, 1940. In the Roosenstein patented system, provision was made for sequentially transmitting the sound and video signals on a common carrier where the limit of time duration of the sound signal modulation was confined to the time interval of interruption of the video signal production.

In systems of the type herein above suggested, 10 general advantages are realized in that it makes possible the conveying of intelligence representative of both optical images of pictures, scenes and the like and sound signal energy (related usually but not essentially so) by the use of a transmitting medium over which but a single carrier is transmitted or radiated. However, disadvantages have been experienced in the prior art arrangements through the inability faithfully to produce the sound in good quality at the receiving 15 end of the system and, at the same time, failure to avoid detrimental reactionary effects between the two forms of transmissions.

In systems of the type where two completely 20 different forms of signals are to be multiplexed, or where a switching mechanism is to be developed to provide for the modulation of the carrier by the two different forms of signals in sequence, the systems of the prior art usually 25 were subjected to the serious disadvantage that undesirable noise components are introduced into the sound reception under the influence of the 30 operation of the sight transmissions.

It, accordingly, becomes a primary object of 35 this invention to provide ways and means by which the audio signals (that is, for instance, relatively low frequency signals such as sound or facsimile) and video signals (that is, for instance, the signals resulting from image scanning operations in television) may be switched or multiplexed, one with the other, in such a way that 40 the sequence of transmissions of the two forms of signals is achieved without any objectionable cross-talk features being introduced, or without the introduction of noise from one signal channel 45 into the other. Thus, the invention contemplates a system where two intelligence signals of different character, such as video, with or without special control signals, are multiplexed with other signals, such as audio or facsimile, with efficient 50 transmission of both without producing interference between the two signals.

A further object of the present invention is that of providing a system for multiplexing the transmission of two completely different types of 55 intelligence signal modulations. For example,

the video signals of a television system, which occupy a relatively wide frequency band when reasonably high detail is to be transmitted, are mixed with signals occupying a relatively narrow frequency band, as would be represented by the audio signals occupying a relatively narrow frequency band or the modulation signals of the second type may originate from facsimile scan-nings, for instance.

In such a system provision is made so that neither form of signal exists simultaneously with the other and, at the same time, provisions are made to avoid the objectionable effects of mutual cross-talk which tend to occur at each instant commutation or switching between the two forms of signal modulation is brought about. In an illustrative form of system herein to be described the two forms of intelligence signals will be assumed to be television video or image signals on the one hand and sound or audio signals which are related (although not necessarily so) to the video signal modulation on the other hand.

Under such circumstances the main sources of cross-talk which usually exist are found in a system of this character in the sound-to-sight cross-talk effect at the transmission end of the system, and in the sight-to-sound cross-talk effect at the receiver end of the system. This is because of the fact that the injection of the sound or audio modulation at the transmitter has a tendency to influence synchronization. Accordingly, it becomes an object of this invention to provide ways and means by which the introduction of sound modulation upon a radiated carrier can be accomplished without in any way altering, varying, or impairing either or both synchronization and video effects.

A system of this character also has as its object that of providing for avoiding cross-talk effects in the receiver between the two forms of intelligence signals. Such cross-talk effects frequently result in view of the fact that because the video carrier is radiated at very high frequencies, it is frequently possible for the video signalling energy to pass directly into the sound portion of the multiplex receiver through inter-electrode capacity even in cases where the electronic conductivity of the commutating or switching arrangements is completely suppressed during the video portion of the cycle of operation.

It is an object, therefore, of this invention to provide ways and means by which this form of capacity cross-talk or, what might be termed "picture chatter," can be avoided.

Further, it is an object of this invention to provide ways and means by which greater fidelity of line and frame or field synchronization may be obtained in sight-sound multiplex systems. It has been found in such connection that serious difficulties and objections in the sound channel result, frequently due to the irregularities of any synchronizing (commonly termed "sync") pulses. Even slight variations in the duration of the horizontal sync impulses which would normally pass unnoticed to the video receiver instrumentality in systems relying for separate carrier transmission for the sound become pulse irregularities tending to provoke extremely annoying and objectionable sound effects in the receiver.

To this end, the present invention contem-plates also the provision of a form of sync signal generator in which the objectionable effects of drift are avoided.

Another object of the invention is that of over-coming the effects of disturbances introduced by

reason of the frame or field synchronizing and, to this end, suitable provision for relay operated means have been made and will herein be de-scribed.

5 A further object of the present invention is that of providing ways and means by which suitably interrupted modulations of the carrier, under the influence of the sound signals, may be brought about. According to the present system, provi-sion is made for developing a high frequency sub-carrier and for frequency modulating this sub-carrier under the influence of sound signals only for a relatively short period during the transmission of the synchronizing pulses. The sub-carrier is of approximately the maximum fre-quency which can be accommodated within the allotted frequency band within which all of the video, the control and the sound signals must be radiated.

20 Another feature and object of the invention is that of providing a system for the transmission of sight and sound signals wherein adequate pro-vision is made for bringing the receiver operation to a steady state condition in an extremely short

25 period of time or, stated otherwise, it becomes an object of this invention to provide a condition of multiplex operation wherein the periods during which the amplitude tends to increase, shall be of extremely short duration. Thus, the transit time, as it were, must be extremely short as com-pared to the pulse duration. The result of this is that it becomes unnecessary, as will later be pointed out, to provide any limiting in the re-ceiver used to detect the frequency modulated sound signals.

30 Essentially the apparatus herein to be set forth comprises, in the transmitting end, a suitable form of sync signal generator which, for the pur-pose of illustration, may be assumed (for an un-derstanding of this invention) to be a form of arrangement providing for the development of both line, frame and field synchronizing signals, as well as the usual blanking signals. The output of this sync generator is then fed to a suitable 35 wave shaping unit and to a peak power amplifier, the output of which serves to control, at pre-determined time periods, a start-stop oscillator, with the start-stop oscillator being set in opera-tion initially under the influence of the pulse signal developed from the sync generator at the 40 end of each scanning line transmission time.

45 Thus, an arrangement of this general char-acter provides an oscillator for the sound sub-car-rier, with the oscillator being in an inoperative state for the greater part of each scanning cycle and then subsequently rendered operative, under the influence of the pulse signals for controlling deflection for limited time periods. This condi-tion occurs under the influence of the sync pulse 50 output from the sync signal generator causing a burst of plate voltage which makes the oscillator operative for the duration of the sync signal. The delayed oscillations are then frequency modulated by the sound or audio (low) frequency 55 control signals under the influence of a re-actance tube of the usual type which is, in turn, controlled by the output from the audio signal amplifier unit after that output has been passed through an image frequency suppressor. The 60 frequency modulated sub-carrier is then sup-plied through a suitable amplifier and, if neces-sary, frequency multiplier, to a combining unit wherein the sight (video) and the sound (audio) signals are combined for transmission.

70 The signals are duly received in a receiver in-

strumentality which has a common video and audio signal amplifier, and in the output of which the sync and, with it, the frequency modulated audio, appears in the negative direction, that is, in the direction of black in the image from which the video signals were developed, so that this signal can be applied directly to control the modulation of the cathode ray beam developed within a suitable image producing tube where desired. At the same time, the signal may be passed through a suitable filter which will filter out the sub-carrier from the sync signal pulses and permit the usual form of sync signals, representing the initiation of the line and the field or frame scannings, to be separated from one another in a suitable sync signal separator unit of known character. The output from the sync signal separator then controls horizontal and vertical deflection of the scanning beam of an image producing tube in known manner to deflect the modulated scanning beam of the image producing tube in exact synchronism with the transmitter scanning operation.

To separate the sound modulation signals from the video and sync signals, it is desirable to pass the complete received signal through an inverter stage which then makes it possible to have the sound modulated peaks occur in the positive direction. These signals are then caused to control the operation of a suitable sound gate and relay arrangement which controls the operative periods of a gate amplifier to which the complete train of signals has been applied. The gate amplifier is thus limited as in its operative periods to those during which synchronizing impulses are received. Output energy from the gate amplifier is supplied to a frequency modulation discriminator circuit, which may be of substantially known character. The detected output of the discriminator unit is then directed through a suitable audio amplifier to a sound reproducing unit.

The foregoing summarizes generally the operation of the transmitter and receiver units, and it, accordingly, becomes an object of this invention to provide ways and means for achieving the foregoing results with circuits which are stable and efficient in their operation and which make possible transmissions of signals of which at least a part become usable in existing forms of television apparatus without any modification of such apparatus.

Other objects, of course, will suggest themselves and immediately become apparent to those skilled in the art when the following specifications are considered in conjunction with the accompanying drawings, in which:

Fig. 1 schematically illustrates one form of transmitter unit;

Fig. 2 schematically represents a form of receiver unit;

Fig. 3 is a schematic representation of a general form of transmitter circuit showing particularly the start-stop form of oscillator and one form of frequency modulator therefor;

Fig. 4 is a circuit arrangement to show particularly the sight-sound injector system for combining frequency modulated sub-carrier energy with the sync pulses;

Fig. 5 is a series of curves to represent the operation exemplified particularly in Fig. 4;

Fig. 6 is a circuit diagram of one form of receiver arrangement to provide for receiving video, audio and control signals to provide image

representations and audio signals suitably controlled; and

Fig. 7 is a series of curves diagrammatic, particularly, of the operation of the receiving instrumentality shown by Fig. 6.

Referring now to the drawings and first to the showing of Fig. 1, the video signals are derived from a camera or image pickup unit conventionally shown in block form at 11. This unit may include any of the well known forms of camera tubes, such as those which have become known in the art as "Iconoscopes" and "Orthicons" of various types, "Dissectors" and the like. The signals resulting from any form of scanning operation thus may be derived from either a storage or a non-storage type of camera tube or pickup unit.

Further description of the pickup or camera unit is therefore believed to be unnecessary and, accordingly, schematic representation has been relied upon for the showing of this figure in that the system herein to be described is adaptable for use in any system wherein video signals are developed as aforesaid.

The resultant output image or video signals from the camera tube or image pickup unit, connected and arranged in known manner, are amplified also in known manner, in the video amplifier conventionally represented at 13. This amplifier, it will be understood, incorporates all of the general and customarily used arrangements, such as the pre-amplifier, the mixing amplifier, the main video amplifier, and if necessary, the line amplifier. The auxiliary controls such as those to provide for distortion correction, for the introduction of suitable background control voltage, and the like have not been illustrated for reasons of simplicity but are to be understood as being included and as being of any conventional character, such as those set forth in the text "Principles of Television Engineering," by D. G. Fink, published by McGraw-Hill Book Co., Inc., of New York, in 1940.

The output signals derived from the video amplifier units 13 are then supplied, as indicated, to a sight-sound injector unit, conventionally represented at 15, which will later be described in detail in connection with a description of the manner by which the audio or sound signals developed are to be combined with those video signals which are representative of the optical image scanned by the image pickup unit or camera tube 11.

For reasons of simplicity, the control of the image pickup unit and the various amplifiers, such as the blanking amplifier assumed to be contained within the unit 13, operating under the influence of a suitable sync signal generator 17, have not been shown. However, schematic representation is made of all connections between the sync signal generator 17 and the sight-sound injector 15 by way of the connections for introducing the horizontal synchronizing signal pulse represented at the terminal S_H , the vertical synchronizing pulses represented as appearing at the terminal S_V , and the blanking pulses for both the vertical and the horizontal represented at the output of the sync signal generator at the terminal marked B_H-V .

The sync signal generator, for the purpose of these presently general considerations, may be of purely schematic nature and of the general type used to provide sync signals for developing co-ordinated response of a receiver instrumentality for both the line and the field or frame scannings. For purposes of illustration, a general

type of sync signal generator is represented by Bedford Patent No. 2,258,943, granted October 14, 1941.

The sound signals which are to be combined with the video signal representations, according to this invention, and which are to be included in the sequential transmission of the two types of signals upon the common carrier, are assumed to be developed in the output of the audio or sound pickup unit, such as that conventionally represented by the microphone 19, although a facsimile scanner may have its output substituted for the microphone 19 and this disclosure should be so understood. The signals from the microphone unit 19 are then suitably amplified in any desired form of amplifier, such as that conventionally represented by the sound signal amplifier 21. An amplifier of this character may be of any desired form, and therefore, has been illustrated in a purely schematic manner.

The output signals from the amplifier 21 are supplied through a filter 23, designated as an "image frequency suppressor." This filter consists essentially of a serially connected inductance elements 22 and shunt connected capacity 24. The filter is preferably tuned by initially setting the circuit constants or by variation of either or both capacity or inductance to a frequency corresponding substantially to half the line frequency at which the image to produce the video signals is scanned, which will represent the highest audio frequency for high fidelity transmission.

It can be shown that where the video or image representation is assumed to be formed in a raster of 525 lines, with the complete image frames being repeated 30 times per second, with interlacing as desired, the line frequency of the synchronizing pulses used to control the receiver unit will be 15.75 kc. Accordingly, the side band limit at which sound reproduction with good fidelity can be produced is of the order of 7.5 kc, so that the cutoff frequency of the image frequency suppressor filter 23 is set at a value just slightly less than half the assumed line frequency of image scanning to achieve highest possible fidelity.

Under these circumstances, there will be developed in the output conductor 25 connected across the termination of the filter 23, sound or audio signal energy of frequencies which vary between 0 and 7.5 kc. for the assumed conditions which must be regarded as illustrative rather than limiting. This signal energy is then supplied by way of the conductor 25 to control the reactance tube 27, later to be described.

At the time that image scanning is taking place under the control of the camera or pickup tube 11, in turn controlled by the sync signal generator 17, output signals or pulses from the sync signal generator, which occur at line frequency and which are designated as appearing at the terminal $S'H$ (also designated as 29) are supplied to the shaping unit 31 by way of the indicated conductor. These pulses should lead slightly with respect to the horizontal sync pulses SH . The horizontal blanking pulses BR are suitable for these keying pulses at terminal 29.

The shaping unit consists essentially of a distorting circuit comprising the capacity element 35 and the potentiometer 37 connected to ground 10, with a variable tap 39 on the potentiometer connecting to the remote end of the capacity 35 and the opposite terminal of the capacity 35 is connected to the control electrode 41 of a peak power amplifier tube 43.

With the arrangement as provided, the line frequency pulses appearing at the output terminal 29 of the sync signal generator 17 are suitably amplified in the amplifier 43 and, at the same time, by virtue of the shaping unit 31, the high frequency components of the wave pulses have been emphasized and the lower frequency components suppressed.

The connection provided between the output of the peak power amplifier tube 41 and the plate or anode electrode 45 of a start-stop oscillator tube 47, is made through the coupling condenser 49 so that at time periods when line signalling pulses appear in the output of the sync signal generator 17 an exaggerated plate voltage pulse will be supplied to the plate or anode of the oscillator tube 47. The result is that with the plate voltage normally supplied to the oscillator tube 47 by way of the connection to a suitable source, not shown, but indicated generally by the plus terminal connected to the terminal 50, there is developed in the oscillator a rather substantial voltage peak which is perfectly coordinated and synchronized in time with the leading edge of the pulse $S'H$ derived from the sync signal generator 17. This supplied high voltage pulse then initiates in the oscillator 47 suitable oscillation frequencies which occur in the parallel resonant circuit including the inductance element 51 and the capacity element 53. The initiation of oscillations in this circuit is thus controlled completely under the influence of the sync signal generator 17 so that each sub-carrier first starts with like phase conditions because all are excited from the same plate pulse as derived from the line sync pulse. The exponential build-up of the sub-carrier frequency output of the oscillator 47 then naturally follows from general laws of transient conditions in oscillatory circuits.

10 The suppression of the oscillations in the circuit of the start-stop oscillator tube 47 is controlled through the suitable adjustment of the shaping unit 31 which is such that energy transferred between the output terminal 29 of the sync signal generator 17 for each line sync pulse and the tube 43 is cut off just slightly prior to the termination of the line synchronizing pulses $S'H$. The result is that the oscillations developed from the start-stop oscillator, whose frequency is determined incidentally by the adjustments of the capacity and inductance elements 53 and 51, are existent only for the duration of $S'H$ and exhibit maximum amplitude at the center of this interval. These oscillations are then supplied to 15 the reactance tube 27 in generally known manner. At the same time, the signal output from the sound signal amplifier 21 is continuously being supplied to the grid or control electrode 55 of the reactance tube by way of the coupling condenser 51 and the R. F.-choke 59. Plate voltage is supplied to the reactance tube 27 continuously from a source of positive voltage, not shown, connected to terminal 61 and fed through the R. F.-choke 63 to the plate or anode 65.

20 The oscillating circuit is shunted by the reactance tube by way of the coupling condenser 67. The grid of the reactance tube 27 is controlled with almost 90° phase-lag through resistor element 52 and condenser 54. The inductance 56 has the effect of introducing slight regeneration into the parallel circuit 51, 53, so that its losses are minimized. With this arrangement it is apparent that modulation of the frequency developed from the start-stop oscillator 25 47 can occur only at limited times in the com-

plete line scanning cycle, as represented in the time difference between the scanning of two successive lines. Although the reactance tube is continually subjected to the influence of the output signals from the sound signal amplifier, the effect in the output therefrom, as appearing in the conductor 69, for instance, is as if the sound signals were of an interrupted character.

Due to the fact that it is desirable to make the sound sub-carrier as high as possible, and due to the fact that the presently allotted wave band for television transmission is only 6 megacycles, it is apparent that the sound sub-carrier may preferably be of the order of 6 megacycles as the center frequency (less the maximum deviation).

With these conditions and due to the fact that the reactance tube 27 usually will not provide substantial deviation under ordinary operating conditions, and that these deviations may be considered, for illustrative purposes at least, as being of the order of 50 kc. it is desirable to provide a frequency tripler stage 71 in order to provide a greater or wider frequency deviation which may approach 150 kc. The output from the frequency tripler stage 71 is then supplied by way of conductors 73 to a power output amplifier 75 which, in turn, is used to energize the sight-sound injector 15 by way of the conductors 71. It was above stated that the output from the video amplifiers 13 and the sync signal generator 17 also were added in the sight-sound injector element 15 so that it functions, thereby, as a combining circuit to control transmitter modulation or modulation of a carrier frequency in any sort of a transmission channel.

With the coordination between the development of the sound modulation signals and the time of production of the synchronizing signals in the sync signal generator, it is apparent that the desired relationship between the time of development of the video signals for modulating a suitable transmitter and the audio signals is adequately and properly controlled so that the various independent signals, representative of sight-sound synchronization and blanking, may, through suitable controls in the sight-sound injector, be applied to an output transmission line 79, for instance, to control or modulate therefrom a suitable carrier frequency for transmission. The carrier frequency which is to be modulated by the output signals appearing as the composite sight-sound signal in the transmission line 79 is constant, during amplitude modulation, with the sight-sound multiplex signals and, accordingly, it is possible to modulate into one and the same very high frequency carrier more than one complete sight-sound program, provided separate intermediate frequency carriers are developed.

Reference may now be made to Fig. 2 for an understanding of the conventional elements of a receiver instrumentality wherein images are produced in accordance with the video signal modulation developed in the transmitter unit described in Fig. 1, and wherein sound signals are reproduced in accordance with the accompanying sound or audio signal modulation as transmitted in multiplexed fashion on the main video carrier.

The receiver arrangement of Fig. 2 provides a common amplifier 85 for the video and audio signals which are received as carrier modulations upon a suitable transmission channel or antenna system connected to deliver the received signals to appropriate input terminal points 86 and 87. The general form of this amplifier is the

usual well known type of wide band amplifier so as to be capable of taking care of the combined amplification of the sight and sound signal modulations (covering a wide frequency range) impressed on the input terminals 86 and 87 without frequency loss.

In this way it will be apparent that within the amplifier unit 85 there are common R. F., I. F. detector and local oscillator stages, as well as various video frequency stages, which are not shown for reasons of simplicity. In this connection no rejector or wave trap circuits are necessary and, as a result, the variable channel band width can be better utilized so that an improvement in definition is obtainable in the final received image.

At the output of the common video and audio amplifier unit 85 a signal, representing all of the video, the video control and the sound or audio accompaniments, appears in conductor 89. This is shown in diagrammatic and schematic form by the wave adjacent to the conductor 89, with portion 90 indicating, for instance, in schematic fashion, the blanking and synchronizing pulses for each line of the image; the portion 91 indicating the blanking and synchronizing pulses occurring at the end of each field of scanning, and the portions 92 representing video signal modulation extending between a level marked black and a level marked white. The sound signal modulations are conventionally represented at 93 and occur as frequency modulations, later to be described in more detail, which are superimposed upon the synchronizing signals, which are, in turn, placed upon the blanking signals according to established practice.

It will be apparent from the diagrammatic showing of the wave form in the conductor 89 that all of the blanking, the synchronizing and the sound signals occur in a direction such that the amplitude thereof extends further in the "black" direction than do the signals represented by black level in the produced image. Signals of such amplitude are frequently referred to as being "blacker than black" in that they extend in a direction which is more negative than that corresponding to black or, in other words, in a direction beyond a cutoff value in the image producing tube.

Contrasted with the control and sound signals, the video or image signal modulation represented at 92 extends within an amplitude range between that marked "black" and that marked "white," so that with these signals being applied to control an image producing tube, modulation of a cathode ray beam may readily occur as it traces the usual scanning raster.

The signal modulation appearing in the conductor 89 is passed then through a conductor 95 and also conductor 96 to control the potential on the grid or control electrode 97 of a cathode ray image producing tube 100 in which an electron beam, conventionally represented at 98, is directed toward the target area 99. For reasons of simplicity, the complete cathode ray or electron scanning beam forming electrode system is not shown, other than for the inclusion of the control electrode 97 and the electron emitting cathode 101.

Deflection of the developed cathode ray beam in both the horizontal (herein referred to also as the "line" deflection) and the vertical direction, relative to the target area 99, is provided by means of suitable deflecting fields illustratively produced by means of the vertical deflecting coils

11

102 and 103 and the horizontal deflecting coils 104 and 105. The same signals which are to provide modulation on the control electrode or grid 97 of the cathode ray tube are passed through a low pass filter system 107 with a cut-off just below 5.5 mc. Hence the sync pulses are stripped of the sound sub-carrier before they are admitted to control the operation of a sync signal separator 109.

10 The sync signal separator is of known character and is for the purpose of separating the line synchronizing pulses, such as those represented at 90, from the field or frame synchronizing pulses, such as those represented at 91. These pulses, when separated, are then fed by way of conductors 110 and 111 to control the operation of suitable horizontal deflection control circuits 112 and vertical control circuits 113 which are then respectively connected by appropriate conductors with the horizontal and vertical deflection coils hereinabove mentioned. The horizontal and vertical deflection control circuits 112 and 113 are of generally conventional character and need not therefore be discussed herein in further detail.

15 The same signals that appear in the conductor 95 and which are used to control the modulation on the grid or control electrode 97 of tube 100 are also passed through the conductor 115 to an inverter stage 117 for the purpose of causing the development of the sound signals in the sound reproducer element 120, which, obviously, may be a facsimile recorder under conditions when the low frequency signals are of the facsimile modulation type. The signal wave form appearing in the conductors 89, 95 and 115 carries the sound in the negative direction. In order to operate a grid-controlled sight-sound separator without image signal chatter, positive sync pulses are needed. Therefore, it is apparent that an inverter stage 117 is necessary in order to place the sound signal modulation 93 in the positive direction on the sync pulses 90 and 91.

20 The output signals from the inverter stage 117 are represented by the wave form 118 appearing adjacent to the output conductor 119. These signals are then applied to a sound-gate system which includes three units—121, 123 and 125. It serves the purpose of eliminating the 60 cycle frame signal noise. The separator unit is the gate amplifier 121 which is suitably controlled under the operation of a gate relay unit 123, which is, in turn, controlled by the gate sync control 125 that is, in turn, energized under the influence of the incoming signal by way of conductor 127. As will hereinafter be explained in more detail, the sound separator 121 is usually a pentagrid tube which is subjected to a dual control. It may be opened only if positive pulses from the input 118 and from the gate relay 123 are present simultaneously. The gate relay 123 will also be described later in more detail but at the present time, the complete gate system may be considered as being for the purpose of eliminating the 60 cycle frame signal noise.

25 It was above pointed out that the gate amplifier 121 should be arranged to be operative only during the periods of time when the sound signal modulation is present. Accordingly, by controlling the operative period of the amplifier 121, in a manner later to be described in more detail, under the influence of the sync signal impulses 90, it is apparent that the sound gate may be opened and shut at proper times to exclude the frame signal noise and other undesired noise.

12

30 The sound gate, in general, must be considered as comprising three essential parts which are regarded as the synchronizing stage 125, the electronic relay stage 123, and the keyed amplifier stage 121. The output signals from the keyed amplifier stage 121 all appear as interrupted frequency modulated sound signals and, accordingly, in order to produce the control on the sound reproducer element 120, such signals are impressed upon a suitable frequency modulation discriminator circuit conventionally represented at 129, which may be of known character in order to detect the said signals and to transform them into amplitude modulated peaks.

35 By reason of the small ratio of signal to repetition period low frequency amplification may frequently be necessary in order to control the operation of the sound reproducer element 120 under the influence of the detected sound signals appearing in the output of the frequency modulation discriminator 129. For this purpose, any suitable audio amplifier 131 may be provided intermediate the output of the discriminator unit 129 and the sound reproducer unit 120, although it will be observed that no limiter is required or shown in the frequency modulation system.

40 Further description of the general form of the sound gate hereinabove represented by the elements 121, 123 and 125 will be made in the reference to Fig. 4, wherein there has been disclosed a suitable circuit for establishing the control hereinabove referred to and diagrammatically represented for purposes of illustration.

45 The circuit shown by Fig. 1 shows various schematic representations of an arrangement to provide for developing the frequency modulated sound sub-carrier and modulating it under the influence of developed sound signals.

50 By making reference now made to Fig. 3, further details and some modifications of the arrangement of Fig. 1 will be noted. In this connection, it will be appreciated that one of the important problems to be considered in developing the sound modulated sub-carrier is that of properly controlling its phase as to the beginning or initiation of the pulses and as to the termination or end thereof.

55 It was explained above, in Fig. 1, that the oscillator tube 47 is in the nature of a start-stop oscillator which is controlled, as to its operative periods, under the influence of the output signals from the sync signal generator 17.

60 If the oscillator were to be permitted to oscillate continuously, instead of being operated as an interrupted element, undesirable noises and beat frequencies would be produced during the time periods of injection of the sound modulation unless the keying of the sound sub-carrier is at an absolutely constant rate. Accordingly, with the arrangement of Fig. 3, and also that of Fig. 1, the output from the sync signal generator 17, when it is passed through the shaping unit circuit, comprising the potentiometer 37 and the condenser 35, will provide the keying pulse energy for the oscillator unit.

65 The shaping unit is so designed that the condenser shunted volume control element 37 permits a variable amount of high frequency emphasis in the output of the sync signal generator, so that the flat top pulses, diagrammatically represented as appearing at the output terminal 29 (the diagrammatic showing is not to scale but merely illustrative), are transferred into a signal with a steep wave front and a decreasing amplitude. This "phasing adjustment" results in

placing the energy maximum of the burst of oscillators at the center of the sync interval, while the sub-carrier amplitudes of the ends of this interval are kept small. This form of energy distribution offers the advantage of not being susceptible to irregularities of the sync generator.

Thus, all high frequency energy bursts which are impressed upon the peak power amplifier tube 43 by way of the coupling condenser 135 are started with the same phase. At the same time, this form of oscillator keying insures that the oscillator will always start its oscillations from zero. Where the sync pulses from the sync signal generator 17 occur prior to the time normally to be expected, the oscillator 47 will start its oscillation with the same advance or delay, and the relative phase of the sub-carrier and the sync pulses will automatically be identical.

The oscillations of the oscillator tube 47 are stopped by removal of the energizing pulses so that the plate energy transmission stops before the sync signal time duration has passed. To accomplish this result, the peak power amplifier may be considered as a high-pass filter and peaking amplifier arrangement such that it essentially comprises a choke fed tube which will be fed, in the instance shown, by way of the inductive element 137 connected serially with the resistor 138 to a source of positive voltage (not shown) connected at terminal 139. This form of connection causes the load on the second half of the tube 43 to become predominantly inductive.

The current flow through the second half of the tube 43 is normally substantially constant, and the first half of the tube is caused to become conducting during periods when positive pulses S'_{H} are derived from the output terminal 29 of the sync signal generator 17. This develops negative pulses in the plate circuit of the first half of the tube 43 during the period of the sync pulses S'_{H} and this, in turn, produces a strong positive peak voltage across the output impedance of the second half of the tube. The input circuit of the second half of the tube 43 is connected to the output of the first half of the tube by way of the parallelly connected resistor and condenser combination 144 and 146. The second half of the tube thus acts generally as a phase inverter and amplifier. The anode of each half of the tube is supplied with positive voltage from the indicated source 139. The signals applied exceed a zero value only for a fraction of the total duration of the horizontal sync pulse output passed to the input or control electrode 141 through the wave shaping unit 35, 37, 39. It is advisable to clip the keying pulse S'_{H} which starts somewhat in advance of the ordinary horizontal sync pulse S_H . This gives the sub-carrier oscillator some time to get started. It was found that the horizontal blanking pulses B_H are very suitable for this purpose of keying the sub-carrier oscillator.

The signal wave form appearing in the conductor 142 from the output of the tube 43 is essentially of the wave form diagrammatically shown adjacent to the conductor. This signal is then supplied across the resistor 143 through the coupling condenser 49 to control the operation of a cathode follower tube 144 by way of the signal pulses applied to the control grid 145 thereof. Output energy from the tube 144 is derived across the cathode load resistor 146 and appears as a strong signal pulse with a low impedance to ground through the condenser 147 and the anode ele-

ment 45 of tube 47. This plate pulse initiates the oscillations in tube 47.

Average plate voltage for tube 47 is adjusted through a leakage resistor element 149, which is of a reasonably high impedance value so that the tube 47 will not undergo oscillations unless a strong positive pulse is applied to the plate 45 by way of the condenser 147. The tube 144 acts as a cathode follower in the arrangement shown, and the cathode supply resistor 148 is made of such high value that the cathode to ground impedance, of itself, does not permit the tube 47 to undergo oscillations. However, at time periods when the energy pulses (such as those diagrammatically shown adjacent to conductor 142) are applied to this cathode follower stage 144, it permits the cathode follower to draw current and it becomes a small impedance to ground which then makes it possible for the oscillator section 47 to undergo oscillations at extremely high frequency. Usually tubes 144 and 47 may be within a single envelope (as indicated) and one type of tube which may be utilized in the combined operation is that known in the art as the 6F8.

The oscillator coil 150, which is shunted by the condensers 151 and 152 (the latter condenser being shunted by a resistor 154 connected between the tube cathode and ground), is connected, it will be seen, so that the tube 47 functions essentially as the well known type of Colpitts oscillator, although the oscillator arrangement which has been shown by Fig. 1 is of a somewhat different variety.

If it is assumed, for purposes of illustration, that a six megacycle band is allowed for the television signals, and if it is further assumed, for purposes of illustration, that the sub-carrier on which the sound frequency modulations are to be produced also approaches a value of 6 megacycles (for example, 5.8 megacycles) then it becomes apparent that the frequency at which the oscillations are developed from the tube 47 may, under the example illustrated, be considered as being of the order of 2 megacycles (actually slightly under 2 megacycles in the assumed example) since the output is to be passed through a frequency tripler stage 71. This is because of the fact that, as above explained, it is generally desirable, in an arrangement of the type herein disclosed, to provide the sub-carrier from a master oscillator oscillating at a sub-harmonic of the final sub-carrier frequency. This is done to obtain a sufficiently wide frequency deviation by any subsequent frequency multiplication. The output from the oscillator 47 is thus subjected to action of a reactance tube 27 controlled in the manner set forth in the description above made of Fig. 1.

With this arrangement the reactance or quadrature tube 27 receives its speech or audio frequency input through the low-pass filter circuit conventionally represented at 23, so that the audio or sound signals are applied to the grid or control electrode 55 through the grid inductance 59. The reactance tube 27 thus is continually connected to the audio amplifiers but the signal input thereto can produce a variation of the sub-carrier frequency only at the limited time periods of sub-carrier generation.

The grid coil 153, in the connection shown, is in series connection with a resistor 156 having one terminal connected to one end of the oscillator coil 150 and its shunting condenser and, also, the same grid coil 153 is in series with a 75 grid-to-cathode capacity 158. The grid coil 153

15

is frequently able not only to reduce any losses which are introduced by virtue of the quadrature tube 27, but frequently even able to overcome such losses.

The grid coil 153 of the reactance tube 27 is equivalent to a variable inductance with losses and by rotating and retarding the phase of the grid voltage (that is, the high frequency voltage) by the coil 153 the result is that a negative resistance appears in parallel to the variable tube inductance. This results in more or less complete cancellation of the damping caused by both the reactance tube and its associated circuit. This also gives regeneration which depends upon the natural frequency of the grid network comprising resistor 156, grid coil 153 and the grid-to-cathode condenser 158. Consequently, the coil 153 is changed until the net effect is best. If the value of the inductance is too high the tube may tend to oscillate. This effect is somewhat desirable because it will tend to reduce and often cancel any amplitude modulation or a signal burst and this effect is otherwise difficult to obtain due to the short time of the burst which makes the ordinary types of clippers for frequency modulation methods where pulsed frequency modulation of the type herein explained is utilized.

With the modification of Fig. 3, the sound or audio frequency signals are assumed to originate, as in Fig. 1, at a sound pickup microphone, conventionally in Fig. 3 represented at 19', and then are fed through a suitable cable or the like 155 into the first stage 157 of a multi-stage resistance coupled amplifier 21 of the usual character. The amplifier may comprise any desired number of stages and preferably includes the use of screen grid tubes connected substantially as shown.

So that flexibility of operation may be provided and so that the signals representative of sound effects may also originate from recordings, a sound pickup head 159 is also arranged to connect with a second conductor element 161 which may, in turn, connect into the second stage 163 of the resistance coupled amplifier 21 by way of a switch instrumentality 165. The switch, in the position shown in solid lines in Fig. 3, is so arranged as to feed the output from the sound pickup microphone 19' through the complete amplifier, but with the switch in the lower position, indicated by dotted lines, the input originating from the pickup head 159 will be utilized. Under these conditions the output from the pickup head 159 is fed across the volume control potentiometer 160 and the cable 161 so that the resultant signal is supplied to the input of the amplifier 163 so that the signal is amplified to the exclusion of any signals developed at the pickup point 19'.

The output signals from the tube 163 are then supplied by way of coupling condenser 166 to the grid of the output tube 164, from which a cathode output is derived, and supplied to the filter unit 23.

The output signals from the multi-stage amplifier 21 are then suitably supplied, by way of the filter 23, hereinbefore described, to control operation of the reactance tube 27. In this operation the output signals from tube 163 feed to tube 164 from which the filter unit 23 connects in the cathode circuit. As suggested by Fig. 1, the filter 23 comprises series inductance elements 22 and shunt capacity elements 24 with a terminating resistance 170. An output signal is obtained by suitably tapping to the resistor 170

16

and then supplying the resultant signal by way of the coupling condenser 51 and conductors 25 and 181 to the grid coil 59 of the reactance tube 27 (as explained by Fig. 1). There is also a signal output representative of the amplified input which is made available at terminal 181 for use, where desired, in monitoring or the like. The center frequency is adjusted through the volume control adjustment at 188 on the resistor 189. The output energy from the oscillator tube 47, as suitably controlled and modulated in frequency by the reactance tube 27, is then supplied, as shown by Fig. 3, for instance, through the conductor 69 and the coupling condenser 166 across resistor 167 into a tube 71 conventionally representing the hereinabove discussed frequency tripling stage.

The frequency tripling, it will be seen, serves to raise the frequency of the sub-carrier from the assumed value in the general region of 2 megacycles and produces the maximum deviation of the assumed 150 kc. in either direction from the assumed center frequency, it being, of course, understood that in the proposed arrangement the deviation normally introduced by way of the reactance tube 27 shall be considered as of the order of 50 kc. in either direction. Of course, where desired, the frequency of the oscillator 47 may be whatever sub-carrier frequency is desired and the frequency deviation of the desired amount may be directly obtained without the use of the multiplier stage comprising the tube 71.

The tube 71, as provided, is of the ordinary variety of frequency multiplier, except for the fact that the grid bias as applied to the control electrode 169 is produced by virtue of a cathode drop appearing in resistor 171 under the influence of limited plate current. The resistor 171 provides bias due to the fact that the screen bias is on at all times so that a D. C. component is available at all times to provide necessary tube bias regardless of the applied pulses. Conventional methods of producing grid bias by grid current are not to be preferred in an arrangement of this character, due to the fact that there is no grid input for most of the time, so that bias production from grid current rectification would be extremely inefficient. This absence of control voltage naturally results from the fact that the oscillator 47 is keyed on only at the times when the sync pulses at horizontal or line frequency appear on the output terminal of the sync generator 29. At other times the oscillator, as above stated, is inoperative.

The power output amplifier, conventionally represented at 75 in Fig. 1, is shown in Fig. 3 by a tube of like number. This tube receives its input signal on its grid, for instance by way of the resistor 176 connected to the transformer 60 coupling provided through the transformer 173 connected in the output of the frequency tripler stage 71. The primary and secondary windings of this transformer are each appropriately tuned to the desired harmonic frequency by means of suitable capacity elements 174 and 175. Output signals from the power output amplifier stage 75 are preferably derived across the cathode load resistor 177 for the tube 75 and are usually taken from across the auto-transformer shown at 179 to energize the conductor 77 which is terminated in an appropriate resistance 181. The sight-sound injector circuit shown and described more particularly herein in connection with Fig. 4 is connected to receive its input at terminal 190, 75 where desired.

In the arrangement shown, there is included also a double diode tube 183 which is connected to the local power supply source (assumed to be connected at terminals 185) by way of the transformer 186. The double diode 183 provides for the development of constant grid bias voltages which are supplied by way of the conductor 187, with the tube 183 being arranged as a full wave rectifier. The diode 183 may frequently be replaced advantageously by an ordinary copper-oxide rectifier.

The tapping adjustment provided by the slider 188 on the potentiometer 189 will readily provide for the adjustment of the sub-carrier center frequency, as above noted. Output signals for the purpose of monitor control or the like may readily be obtained at either of the output terminals 190 or 191 indicated, these signals being representative, in one instance, of the sound or audio signal representations and, in the other instance, of the bias voltages obtainable.

In the broad reference to the circuit of Fig. 1, the sight-sound injector 15 has been referred to as the element wherein the separate signals representing the video, the synchronizing effects, the blanking controls and the frequency modulated sound sub-carrier are to be mixed and combined. Also, in the broad and more general reference to Fig. 1 to give a more generalized description of the system, it was stated that this sight-sound injector element would be further explained in reference to the showing of Fig. 4.

Now making reference to Fig. 4 and bearing in mind the fact (as explained with Fig. 1) that the video signals which reach the sight-sound injector 15 from the video amplifier 13 are stripped of all of the D.-C. components in view of the fact that it is customary, in television operations, to use the so-called A.-C. amplifiers, it becomes necessary in the sight-sound injector unit 15 to complete the video signals, so to speak, by the addition of the D.-C. component, the blanking or pedestal pulses and the synchronizing pulses. The latter of these two controls is derived from the sync signal generator 17 connected into the sight-sound in the manner diagrammatically shown by Fig. 1.

The particular apparatus shown by Fig. 4 for forming the sight-sound injector unit comprises an input terminal 191 to which, it may be assumed, the horizontal and the vertical synchronizing pulses (Sh and Sv of Fig. 1, for instance) are applied. The general wave form of these signals is shown more particularly by curve A of Fig. 5, although, in an explanatory manner (but no curves shown are to be considered as drawn strictly to scale), represented also by the wave reference immediately adjacent to the terminal 191.

If reference is made at this point to curve A of Fig. 5, it will be seen that the horizontal and vertical sync pulses, as initially received at the terminal 191, consist of pulses which are positive in polarity with respect to ground. As is evident from Fig. 1 all of the pulses are of approximately equal amplitude, with the designations h representing the horizontal pulses, and the designations v representing the vertical pulses, for instance. These pulses are similar to the form of sync pulses recommended by the FCC and RMA for present standards, except insofar as the omission of the so-called preparatory or equalizing pulse is concerned and except for the provision of a second slot of 0.04H width (see Fig. 5A at S₂). The produced signal series is impressed upon a

twin triode amplifier tube 193 by way of the usual coupling condenser 194 and grid resistor 195.

The first half of the twin triode 193 serves to amplify the incoming pulses to about 10 times the impressed voltage while the second half of the tube serves as an inverter and clipper, after which the signals are passed through the triode coupler tube 197 which is connected as a cathode follower so that the output is derived across the cathode load resistor 198 which is tapped at the point 199, for instance. The double triode element 193 is of any desired type such, for instance, as the 6N7 and the two stages are connected one with the other in such a fashion that the first stage is blocked between two pulses while the second conducts through, under zero bias conditions by a resistor 196 of several megohms.

The output signals derived across the cathode load resistor 198 of the tube 197 are shown conventionally by curve B of Fig. 5, where again the vertical sync pulses are represented as v and the horizontal sync pulses as h , although amplified in character from those impressed at the input terminal 191.

25 The resistance condenser network 201—202 is connected at the line 203 serving as the output conductor for supplying the sync signals to the injector unit keying tubes 205 and 206. This resistance condenser network provides appropriate bias for the output voltage which appears in the conductor 203, as indicated by the wave form of curve B of Fig. 5 heretofore mentioned. The conductor 203 then connects to the screen electrode 207 and 208, respectively, of the keying tubes 205 and 206, with the connection to the screen electrodes being made in parallel.

Under normal operational conditions, the wave form, as shown by curve B of Fig. 5, is such that the pulses extend within a voltage range from 40 approximately 150 volts negative in the interval between successive pulses. This variation in voltage thus provides ways and means by which the keying tubes 205 and 206 draw no current except during periods of synchronization, by reason of the fact that the negative portion of the impressed voltage wave tends always to drive the tube beyond a cutoff state.

50 The sound or audio sub-carrier coming from the output of the power amplifier 75 (Fig. 1), for instance, is impressed upon the injector unit by way of the cable or conductor 77, as above mentioned in connection with the description of each of Figs. 1 and 3. The sound or audio modulation signals, as was above explained, are in the form of interrupted frequency modulations of a sub-carrier and consist of bursts of waves of a frequency approaching the maximum frequency in the allotted spectrum, with the accurate timing and initiation of the carrier having been effected 55 under the control of the horizontal blanking pulses B_H which occur at line frequency which are applied at terminal 191. These pulses lead the horizontal sync pulses by about 2% of a line period and thus the start-stop oscillator has (with present standards) over one microsecond more time to start oscillations which will conserve full strength during the sync interval. Thus, the sound modulated sub-carrier pulses which appear in the cable 77 and which are further diagrammatically represented by Fig. 5 (curve C) are coincident with, and interior to, the horizontal sync pulses represented in each of curves A and B of Fig. 5 which initially appear at the input terminals 191 and appear in amplified form at the out- 60 70 75 put terminal 199.

It can be seen, from the connection of the modulated sub-carrier pulses from the cable 71 into the grid or control electrodes 209 and 210, by way of the coupling transformer 211, which has its secondary midpoint 212 connected to ground, as indicated, that these signals are applied in push-pull fashion on the keying tubes 205 and 206. It, therefore, becomes a problem in the operation of a system of this character to eliminate the transients so introduced. This is done by the described balanced to ground condition provided by way of the ground connection from 212 on the transformer secondary through the resistor 213, and shunting condenser 214. On the other hand, the unmodulated pulse form derived from the conductor 203 is applied to the two keying tubes 205 and 206 in parallel. The result is that, under these circumstances, the tank circuit of tubes 205 and 206, comprising the primary winding of transformer 215, with the variable condenser 216 across the same (the condenser usually being shunted by a resistor 217) is not excited by the unmodulated sync pulses as applied to the tubes in parallel by way of the conductor 203, but only by the incoming sub-carrier energy, Fig. 5—C, and this is only for the duration of the sync pulses of Fig. 5—B. There is also included a resistor 221 across which there appears the keying voltage alone without the sub-carrier modulation, as shown by the drawing. This gives a negative pedestal to the sub-carrier oscillations so that the sync position of the two components results in a curve form such as shown by curve Fig. 5—D. However, the keying tubes 205—206 can only become conducting as far as the incoming modulated sub-carrier appearing in the conductor 71 is concerned at time periods when sync signals are present in conductor 203 and applied to the tube grid elements 207 and 208. At times when output energy representative of the incoming sub-carrier is passed from the tubes 205—206, it will be applied to the circuit of the diode 219 by way of the secondary of the transformer 215, which secondary is appropriately tuned by the tuning condenser 220, for instance. These transfer pulses of modulated sub-carrier energy then are of the general form of those shown by Fig. 5—D after they are combined with the sync pulses which appear in negative polarity across resistor 221.

It will be noted, however, that under these circumstances a transient signal, such as that marked on curve D of Fig 5 at x, tends to be developed. This transient effect is probably due to the fact that the back-kick from the controlling sync pulse occurs before the sub-carrier oscillations have died down completely. A transient of this type is most undesirable and it is important that it be eliminated before reaching the main transmitter output stage consisting, for example, of tubes 223 and 224, later to be described both as to their connections and operations. The presence of transients of the type indicated at x on curve D of Fig. 5 would tend to produce, in the finally viewed image representation at the receiving point, the effect of a sound modulated high frequency pattern which, of course, would be objectionable and conspicuous.

So as to clip these signals, the diode tube 219 which, for example, may be of the 1-V type, is provided between the superimposed sub-carrier voltages appearing across resistor 221 plus the secondary of transformer 218 and the final transmitter output tube combination 223 and 224. The

load resistor 225 is so adjusted that clipping occurs at an appropriate intermediate voltage shown, for instance, at curve D of Fig. 5, as the level indicated by the dotted lines. The result is that there is obtained across the load resistor 225 a complete intermodulation of the sync pulse energy and the sound sub-carrier energy without transients. This effect has been exemplified, for instance, by curve E of Fig. 5 and diagrammatically represented by the conventional wave form indicated on Fig. 4 by the curve adjacent to resistor 225.

These signals then are transferred to the final modulator tubes 223 and 224 by way of the coupling condenser 227. Appropriate bias on the electrodes 228 and 229 to which the signals are supplied may be set and adjusted through the use of a resistor 231, which may even be variable, where desired, which is connected to the positive voltage supply line 232 receiving positive voltage from a terminal source (not shown) connected at the point 233. The bias obviously can be set in such a manner that the final transmitter modulator tube combination is 100% modulated by the peaks of the sound sub-carrier and approximately 90% modulated by the peaks of the unmodulated sync pulses alone. With a setting of this character, the multiplex transmissions may be carried forward without any undesirable clipping or limiting action which contributes greatly to the overall fidelity of the sound transmission.

Since it is desired that the video signal modulation should be combined with the produced sound signals appearing as frequency modulated pulses superimposed upon the line sync impulses, provision is made in the portion of the circuit shown in Fig. 4 to the right of the transmitter output tubes 223 and 224, for introducing the video signal and combining it with the frequency modulated sub-carrier for the audio signal, in the manner described.

The video circuit shown is, in many respects, like that described in presently pending application for United States Letters Patent filed by this applicant on May 7, 1943, and identified as Serial No. 485,982, now U. S. Patent No. 2,366,358, and entitled "Television amplifier circuits." In a system of such character, the video modulation signal is impressed at the video input terminal 239 and supplied to the amplifier 241 through the coupling condenser 243. The grid resistor 245 is connected across the grid cathode circuit of the amplifier 241 to ground 10.

As explained in the mentioned copending application, a diode 247 may be connected between the grid or control electrode of the amplifier 241 and ground 10 with the cathode of the diode connected to the grid or control electrode and the anode thereof to ground in order to provide ways and means, as also explained in the copending application, by which the so-called D.-C. component may be added or restored in the video signal supplied to the amplifier 241.

Output signals from the cathode follower coupling stage 241 are derived across the cathode load resistor 249 therefor and are supplied, in turn, through a diode 251 which serves as a coupling element to supply the resulting signals upon the control electrode 253 of the amplifier 255.

With a circuit of this character, it is the function of the diode 251 to provide a conductive path between the tube 241 and the amplifier 255 whenever the cathode element 257 of the amplifier 255 becomes more positive than the average bias of the signal source, which will be measured

by the cathode output from the tube 241. At such times the diode 251 becomes conducting and signal voltage is then applied through the diode to the grid or control electrode 253 of the tube 255 and the grid is thus caused to follow the output of the tube 241.

A circuit of the type described also provides an arrangement whereby provision is made for keying the output tube 255 at certain time intervals, which will be assumed herein to constitute those intervals during which blanking pulses, identified as Bv-H on Fig. 3, for instance, are developed from the sync generator 11 and are applied, in the arrangement shown, to the blanking signal input terminal 259.

In the manner also explained in the copending application, the applied blanking pulses are passed through the coupling condenser 260 and conductor 261 to the grid or control electrode 262 of a keying control tube 263 from the output of which signals are applied to the keying tube.

The tube 263 serves to control the operative periods of the tube 265 by way of the connection of the control electrode 266 thereof to the output load resistor 267 through the coupling condenser 268. Accordingly, it becomes evident that the cathode 269 of tube 265 will follow exactly the blanking pulse periods as applied to the input terminal 259 and will, accordingly, control the operation of tube 265 by virtue of the connection of the outer or screen electrode 271 thereof to the cathode element 269 of tube 265 by way of the conductor 272. Thus, provision is made whereby the keying periods of the tube 255 to transfer the video signal impressed at terminal 239, with the D.-C. component added thereto and the blanking control also supplied, into the diode element 275 which has its anode connected to the cathode 257 of the keying tube 255.

The arrangement so far described in connection with the application of the video signal essentially constitutes a mixer amplifier which produces a blanking pedestal within the video signal but not yet the sync pulses as such. These are injected within the stages 223—224 together with the sound sub-carrier modulation. It is a cascade of cathode follower stages with each output cathode connected to the next input grid either galvanically or through electronic valves. The diode 275 essentially provides the output coupling for the system while the diode 251 serves as the input coupling. The output of diode 275 is connected to the No. 1 grids 276 and 277 of the output tubes 223 and 224 and feeds across the resistor 278 which connects at an appropriate point to the load resistor 279 for the composite signal.

At the output terminal 280, signals representing the combined video blanking and sync pulses, with the audio modulation added as a frequency modulation of the sub-carrier, become available, although it should be apparent that the screen electrodes 228 and 229 of the output tubes 223 and 224 do not receive the simple super sync pulses directly but rather the combined super sync and sub-carrier more schematically represented by curve E of Fig. 5 and also by the diagrammatic wave form conventionally demonstrated adjacent to the output resistor 225 of the diode 219. The resultant output signals as shown by curve F of Fig. 5 (and also by the wave form adjacent to conductor 281 with the sound portion of the signal indicated as s) are

then supplied across the conductor 281 and finally appear as a mixture of the various groups of signals at the output terminal 283 connected to the terminating resistor 285 of the conductor.

It will be apparent that by adjustment of the tap 286 across the cathode feeder 279, the grid bias of the power stages 223—223 may be adjusted, whereby a control of the adjustment of the height of the synchronizing pulses carrying sound modulation in the form of the interrupted frequency modulation has been made possible at the cable input. The amplitude of the combined signal then may also be controlled by an adjustment of the tapping point 286 for connecting the output terminal 283 to the terminating resistor 285 of the load conductor 281. Output signals at terminal 283 are then fed to any desired form of transmitter channel (radio or wire line) from which they can be supplied to an appropriate receiver for producing image representations with usual accompaniment.

The description of Fig. 2 presented a general analysis of the receiver instrumentality. By that arrangement, explanation was made whereby the signals representative of the image portion of the transmission are segregated from the synchronizing and sound accompaniment signals.

The circuit diagram conventionally represented in Fig. 2 then also set forth the general and schematic arrangement whereby the incoming signals were fed through a suitable sub-carrier filter to actuate or control the sync signal separator circuit. These same signals were also then applied to an inverter stage from the output of which signals were applied to the sound gate relay system and thence to the sound reproducer.

In the arrangement of the circuit of Fig. 6, further details of the receiver instrumentality have been shown in such a way as to make clear the time division basis of operation. As far as the receiver per se is concerned, it will be appreciated that one of the important features thereof is the sound gate arrangement schematically represented by Fig. 2. The purpose of this sound gate is to eliminate the 60 cycle frame signal noise which is otherwise produced by the vertical sync signal. To this end an electronic switch is needed which connects the sound receiver to the input at regular line intervals and constant duration, whether or not there is a frame signal being transmitted. To accomplish this result, a so-called "sound gate," which will be described below, is provided. In the arrangement as schematically shown by Fig. 2, it will be seen that there are essentially three main portions included, of which the element 125 constitutes the synchronizer stage, the element 123 constitutes the relay stage, and the element 121 constitutes the keyed separator or gate amplifier.

Essentially, as above stated, the sound gate might be classified as a keyed video-audio signal separator which is so controlled as to provide for elimination of the frame signal noise. To this end the relay unit is made to respond to each incoming horizontal or line sync pulse, and the relay unblocks the gate amplifier or separator for its holding time, which is made adjustable and preferably slightly less than the line sync period. Elimination of the frame signal noise is only accomplished by rigorously holding the time constant of operation stabilized and of substantially fixed duration during the pulse input.

The sound gate system should be triggered by the wave front of the pulse input and should

respond only at predetermined time intervals so that if a pulse arrives, for instance, at a frequency of twice the line frequency, which is a condition that might be experienced during the frame signal transmission, the relay should not respond to these pulses but only to every second pulse. Frequency selection of this character thus becomes important in the operation of a combined sight-sound multiplex system.

The circuit arrangement of Fig. 6 thus constitutes a sound gate relay system which is extremely regular in its operation and which does not introduce or contribute any additional noise of its own to the sound reproduction. Where the gate relay system 123 is closed, no video signals should be able to pass through the keyed gate amplifier or separator stage into the sound reproducer 120. It is the function of the complete sound gate circuit to provide operation of the system in such a way that the actual periods of sound reproduction from the sound reproducer element 120 shall be limited only to those periods when sound bursts occur as frequency modulations superimposed upon the line sync pulses and lasting for a fractional portion of the time duration of each. The ear of the observer then must be relied upon to fill in, so to speak, the remaining sound which actually is not transmitted.

Referring now, in more detail, to the circuit shown by Fig. 6 of the drawings, the composite signal which was assumed to be present at the output or load terminal 283 (see Fig. 4), or which was present in the cable 281, is applied in the output of the cable 281 across the terminating resistance 285 (these portions of Fig. 6 are numbered equivalent to Fig. 4, for convenience of reference) and is then fed through the resistor element or volume control unit 287 to the cathode element 289 of an amplifier tube 290.

The tube 290 thus constitutes a cathode driven amplifier with the volume control established by virtue of the variable resistor 287 which, like the resistance 285, is of relatively low value and usually of the general order of 100 ohms each. Plate voltage for the amplifier tube 290 is supplied from a source, such as the known power supplies not shown, connected with its positive end at the terminal 291 and its negative end customarily connects to ground at 10. The voltage is then supplied to the tube anode by way of the filter network including the series resistances 292 and condenser 295, as well as the plate impedance, represented by the resistor 293 in series with the inductive peaking element 294.

The control electrode of tube 290 assumes a bias which equals the negative peak of the swing of the cathode 289. This bias is maintained for at least the time constant which is measured by the R-C network comprising resistor 282 and capacitor 286. Bias is produced by the grid current flow during negative peaks of the cathode voltage. Resistor 288 is of low value and serves primarily as a suppressor against undesirable oscillations which the tube 290 is apt to undergo in a system of this type where this tube would act as an oscillating cathode follower.

By virtue of the grid current flowing in the tube 290 when it is cathode driven, the output from the tube which will appear in the load connection made through conductor 296 is an amplified sight-sound (video-audio) multiplex signal of the character conventionally represented adjacent to cable 281 in Fig. 4, with the proper D.-C. component added thereto and without polarity

inversion. Therefore, in the output connection from the tube 290, which is supplied to the amplifier tube unit 297 by direct connection to the control electrode 298 thereof, there is a positive video modulation upon the grid or control electrode 298.

In the arrangement shown, the inductance element 294 constitutes a shunt peaking element. While it is represented in the connection particularly shown by Fig. 6, that the tube 290 is a cathode driven tube, this particular form of connection is only one of several possibilities and is herein represented by reason of the fact that, for convenience of illustration, the input is represented in the nature of a cable such as that shown by Fig. 4, and cathode driven amplifiers can be used to advantage in such connections because they yield an output without polarity inversion. However, where the output of the transmitter system, such as that shown by Fig. 4, is applied to a radio link so that the complete signal including the video, the sync and the sound modulation appearing upon the sub-carrier are all used to modulate a radio carrier in negative modulation, then the conventional grid controlled type of video amplifier may well be substituted for the repeater element 290, if desired.

The signal output from the repeater element 290, as it appears in the conductor 296, is then fed through the amplifier and inverter stage 297 so that the input signal can be repeated without polarity inversion and at a low output impedance value at the cathode, and with inverted polarity at the plate. The output signal for controlling the cathode ray image producing tube 100 is supplied to the conductor 96 by way of the connection from conductor 299 as the signal is derived across the cathode load resistor 301 for the tube 291 is shown.

At the point 303 the cathode output signal of the tube 297 is supplied into two branches, of which one branch leads to the control electrode 97 of the image producing cathode ray tube 100 by way of the series peaking coil 304, and of which the other connection leads into the sub-carrier filter 107 which was also described in connection with the reference hereinabove given to Fig. 2 and which will later be further explained in connection with the description of the sync signal separator and deflection control circuits for the image producing tube 100.

At the moment, however, it may be sufficient to state that the signal output from the filter 107, as it appears in the conductor 305, is a signal without the sound modulation and negative peaks of sync pulses. It has substantially the conventional wave form of a presently recognized standard form of television video signal without any sound sub-carrier, but has no preparatory pulses and double slotted frame signals, so that, consequently, it is of the general form of Fig. 5A.

Provision is also made for deriving from the inverter stage 297 a second signal which will be obtained at the plate or anode element 307 thereof by way of the conductor 308 and coupling condenser 309. This signal will be applied, as explained in connection with the schematic representation of Fig. 2, to control the combined sound gate relay unit which includes the synchronizing element 125, the relay element 123 and the amplifier or separator unit 121.

Accordingly, the sound receiver portion of the circuit is driven from the plate circuit of the inverter stage 297 where there are produced in-

verted sight-sound multiplex signals with positive peaks. The load resistor 311 of the inverter stage 297 is preferably shunted by a small variable condenser 313. Adjustment of the condenser 313 provides ways and means by which the high frequency gain may be reduced. This is desirable in circuits of this nature because the capacitive portion of the load across the cathode, as it appears at point 303, results in an emphasis of the high frequency components across the plate or anode load resistor 311. If no counteracting features are introduced and the effects of the high frequencies nullified, cross-talk will appear in the sound channel leading to the sound reproducing element 120 and the sight-sound separation would not be complete.

Generally speaking, it is desirable that the adjustment of the condenser 313 be such that there is a one-to-one ratio of high and low frequency amplification across the line 315 connected to the terminal of the condenser 309 which is remote from the tube 297. This provides proper relationship between the sub-carrier and video signal amplification.

It is, of course, to be appreciated that the condenser 313 may be adjusted once and for all in its operation in which case the sound gate mechanism of the tubes 320, 330 and 340, later to be described in more detail, shall operate as desired.

In considering this operation, the sound gate circuit which is fed from the output of the inverter stage 297 functions in such a manner that the final keyed separator tube 340 is keyed by both the sound and the control signals. In this way the output from the plate of the tube 297 is applied by way of the coupling condenser 309 and the conductor 315 to the No. 3 control grid 317 of tube 340 and also is applied through the same coupling condenser 309 and the connection 319 to the control grid 321 of the gate synchronizing tube 320, as indicated.

The keyed separator tube 340 is preferably of the so-called pentagrid type. One tube type which has proven very satisfactory in this use is that known in the art as the 6L7 in which two successive grids are provided for dual modulation of a common electron current. The No. 1 grid is usually designed for remote cut-off, but the No. 3 grid has a sharp cut-off and, therefore, requires relatively small cut-off voltage. Accordingly, the separator tube 340 is preferably keyed in such a manner that the signal input, as shown, for instance, by curve A of Fig. 7, is applied to the No. 3 grid 317 by way of the conductor 315 and the gate relay pulses, later to be disclosed and described in more detail, are applied to the No. 1 grid 325 in a manner also later to be described from the output of the relay tube 330.

The synchronizing stage 320 has broadly two functions, of which the first is to keep the voltage peak at the input cable or conductor 319 at zero potential, which is desirable to maintain both satisfactory separator action in the stage 340 and proper sync clipping in the stage 320 over a wide range of signal amplitudes. D. C. insertion is obtained by the grid current which flows in the stage 320 which operates with a very high grid leak resistor 327 connected between the grid 321 and ground where the cathode of the tube 320 is connected, as indicated. The second function of the synchronizing stage 320 is to provide appropriate trigger pulses for the relay stage 330. As the grid-to-ground peak voltage is fixed by D. C. insertion provided by the flow of grid current and by means of a high resistor 327, the

clipping bias for plate current may be adjusted by the screen resistor 329. It is also desirable in the synchronizing stage that preliminary frequency selection be shown if the input frequency is to be doubled by the slot signals.

The plate voltage output from the synchronizing tube 320 is differentiated by means of the small capacitor 332 and resistor 337. The differentiated pulse appears at point 333 (see curve B of Fig. 7), as it appears across the load resistor 337. From curve B of Fig. 7, it can be seen that all of the regular horizontal sync pulses appear at equal amplitudes and are stripped of their sub-carrier modulation by reason of the capacity 335 appearing across the relatively high resistance 337. Pulses, however, which occur at double the line frequency during the slots c (see curve A of Fig. 7) in the frame signal, experience some reduction in their amplitude and this is brought about by the very high value of plate resistor 331 which is unable to supply the normal plate voltage at the necessary rate. The system is so designed that once a signal is passed, the complete voltage on the tube 320 drops noticeably and it takes approximately one-half a line period (of the general order of 30 microseconds or more with existing standards) to restore plate voltage in the tube to the original level. This preliminary suppression of the double line frequency by itself, however, is insufficient to provide complete frame noise elimination in the signal which would otherwise be present due to the general character of the vertical sync of the signal received.

Accordingly, to obtain the general result, as aforesaid, a single pulse relay 330 is provided. Various forms of tubes may be used for the purpose of this relay, but one tube which has been found satisfactory is that known in the art as 6N7. A tube of this character in the circuit with which it is associated essentially provides and fulfills three conditions of which the first is that one output pulse should be provided for each regular sync input pulse, and, second, that the duration of the output pulse should be made adjustable and completely regular, and, third, that there should be no response from the relay system to any input which occurs sooner than at line frequency intervals. In the arrangement shown, the circuit for the relay tube 330 is intended to fulfill the foregoing conditions.

The gate width is adjusted by virtue of adjustment of the condenser element 341 and the resistor element 343, while the selection of pulse frequency is provided by the blocking system in the form of the resistor 345 and the condenser 347. In this arrangement the cathodes of the two sections of the relay tube 330 are connected together and are connected to ground 10 by way of two resistor elements 349 and 351, of which the latter is customarily several times the size of the former. The circuit provided by way of the condenser 341 and the resistor 343, which merely serve to adjust the gate width, is connected so that the signal pulses appearing at the point 333 as the output of the sync tube 320 may be fed through the series connections shown and the condenser 341 to the grid or control electrode 354 of the second half of the tube 330 so that the resistor 343 serves as the leak resistor of the system. In the operation the system is so adjusted that the second half of the relay tube 330 is normally constantly conductive in that with the arrangements shown the grid 354 is conductively connected to the cathode at all times through the variable resistor 343 but on the other hand,

with the grid 355 of the first half of the relay tube being connected to the cathode through the resistance portion 345 of the pulse frequency integrating circuit and through the resistor 349, it becomes evident that the resistor 349 will serve to provide a permanent blocking bias on the first half of the tube 330 during all periods when the second half of the tube draws current. It will be understood, of course, that, where desired separate tubes may be substituted for the double purpose tube herein illustrated but the operation is, in all instances, the same.

If, now, reference is made to the curve B of Fig. 7 and it is assumed that a negative wave front is received through the differentiating network provided by way of the coupling condenser 353 and the plate resistor 355 of the first half of the tube, then a feed back action within the relay system takes place. The negative pulse is transmitted to the grid or control electrode 354 of the second half of the relay tube 330 with the result that emission in the second half of the tube is momentarily interrupted. The cathodes of each half of the tube are shown as being connected so that both cathodes perform a voltage drop when the grid 354 goes negative but the grid element 355 is unable to follow this effect by reason of the grounding provided by way of the condenser 347.

Consequently, within the first half of the relay tube 330, plate emission takes place first, and second, the grid condenser 347 receives a negative charge due to grid current following in the first half of the tube and the plate current pulse in the triode section of the tube reinforces the incoming signal as it is impressed across the resistor 355 so as to make the plate still more negative. Consequently, feed back action takes place which speeds the relay response up so much that the gate opens, so to speak, with a delay of only a minute fraction of one sound sub-carrier period. The holding time of the circuit is determined by the circuit including the plate or load resistor 355 serving as a part of the differentiating network with the condenser 341 and the resistor 343 which connects the grid 353 to the tube cathodes. The entire arrangement and its holding time can be adjusted through adjustment of the resistor 343, for instance. Generally speaking, the time constant values should be so adjusted that the holding time of the relay is slightly less than one horizontal sync pulse duration, or with double slotted pulses, slightly longer than one horizontal sync pulse which, according to presently recommended standards, necessitates the time constant being adjusted to the order of seven per cent of a line period with a 525-line image transmission, which means a time period according to presently-recognized standards of the order of 4.4 microseconds.

It was above stated that the pulse frequency selection which was made by the relay 330 was determined by the resistor 345 and the condenser 347 and also stated above was that the condenser 347 received a grid current pulse during periods when the first half of the tube 330 draws grid current. In the operation of the system, the resistor 345 is so arranged that the charge across the condenser 347, as represented, for instance, by curve C of Fig. 7, will require approximately 70% of the line period (shown as H in Fig. 7) to leak away through the resistor 345. If this is done, the time constant of the resistance condenser combination 345—347 is chosen equal to

or longer than $\frac{1}{2}$ the line period as represented

$$T_g \geq \frac{H}{2}$$

where T_g is time constant of the gate and H the line period. Thus, it will be evident that the relay itself will be unable to respond to any pulse which is impressed thereupon at a period prior to one occurring at a time period equal to one line period of the transmission subsequent to the last preceding pulse which effected a control operation. Where any pulse arrives prior to such a time, as do the slot signals S_2 (see Fig. 5, curve A) within the vertical or framing signal pulse, for instance, the received pulse will be impressed upon the relay unit when the grid or control electrode 355 of the first half of the tube 330 is unusually negative and although the cathodes of the tube sections under the control of the incoming wave do change their potential and drop in the negative direction, there is no plate current available within the first half of the tube.

The net result is that the keyed amplifier stage 340 is being unblocked by regular pulses shown in Fig. 3, curve D, obtained across resistor 355 and is fed to the first grid 325 of the keyed separator 340. This stage, however, is not unblocked for intermediate pulses or for conditions corresponding to slots in the framing or vertical signal because there is no emission taking place within the first half of the relay tube 330 and, therefore, no signal at its output circuit. Consequently, there is obtained across the tuned plate circuit 359 of the amplifier tube 340 and under control from both grids 325 and 317 a plate current wave form which has been schematically represented by curve E in Fig. 5 in which there is an absence of any traces of any transients due to the occurrence of the frame signal as an interruption in the regular sequence of line signals.

These keyed pulses occur at time periods when the keyed amplifier stage 340 is unblocked by reason of a cessation of current flow in the first half of the relay tube 330 so that a positive potential is applied to the No. 1 grid 325 of tube 340 through the coupling condenser 361. Simultaneously, the audio modulations, as hereinbefore represented, are supplied to the No. 3 grid 317 of the keyed amplifier stage 340 by way of the conductor 315. With the time constant of the network 355, 341 and 343 being adjusted, as above noted, so as to be longer in time than $\frac{1}{2}$ a line period the slot effect in the vertical signal does not open the keyed gate amplifier stage 340. The result is, accordingly, that the tube 340 can draw no plate current for the slow portion of deflection cycle but is limited to current flow during the snap back or return trace period by reason of the unblocking of the tube. By the potential applied to grid 325 there is an electron current to modulate and during this period, the modulated sub-carrier is applied to the grid 317 so that the output as supplied from the plate or anode 363 to the tuned circuit 359 is an audio modulated signal which is substantially free from any video cross-talk effects.

In one conventional system where the multiplexing is applied to television operations for the image production results in a traced image composed of 525 scanning lines, for instance, repeated at 30 frames per second the line period for each of the scanning lines thus is of the order of 63 microseconds. If, now, the selector circuit which contains 75 trots, as above named, the time periods at which

the audio modulation can be transferred to the tuned plate circuit 359 of the keyed amplifier stage 340, and if this selector circuit has its time constant set at the order of 50 microseconds, for instance (which is slightly longer than $\frac{1}{2}$ the line period), it is apparent that the amplifier 340 will be keyed at only the desired time periods and then the tuned circuit 359 will, at such time periods, receive bursts of frequency modulated sub-carrier which are considerably amplified. The output from the tuned circuit 359 is fed by way of the coupling condenser 365 into the double diode tube 367 so as to be applied on the plate or anode elements thereof in such a way that the diode tube 367 operates substantially as the usual form of frequency discriminator whose output is derived across the cathode resistor 369 which connects to ground 10 by way of a second resistor element 371. Both of these resistor elements are bridged or shunted in a well-known manner by capacitors 373 and 375. Any other form of FM discriminator is equally well adaptable and may be substituted.

In an arrangement of the type described, long intervals of time and silent periods occur between the so-called sound "slices." As was above mentioned and pointed out, the effective complete sound signal is to be conveyed to the ears of the listener through the transmission of only approximately 4% of the total sound present. Consequently, reasonably high audio frequency amplification is desirable. To this end the output from the discriminator 367, may be supplied by way of an appropriate filter 377 to the amplifier proper.

The signal output from the discriminator 367 is then supplied through coupling condenser 366 to the control electrode of a cathode follower tube 368 to the cathode resistor 370 of which a connection is made to the filter 377 by way of the coupling condenser 372. The filter 377 comprises series inductance elements 374 and a shunt capacity 376. At the termination end of the filter there is a resistor 378. In order to supply signals to the amplifier input, an appropriate form of volume control 383 may be utilized. The amplifier proper usually comprises two power stages 385 and 387 operated in conjunction with a more or less conventional pre-amplifier and phase inverter stage 389. It may be noted that from this point on, audio amplifiers of substantially conventional nature may be utilized. Therefore, the amplifier herein to be described may be considered illustrative and as being detailed herein largely for the sake of completeness of disclosure. When the signals are supplied to the pre-amplifier and phase inverter stage they are first supplied from the control grid 391 of the first of these stages and from the output of this stage and the signals are fed by way of the capacity coupling 393 to both the grid 395 of the inverter stage and the control electrode or grid 397 of one of the push-pull stages. In the arrangement disclosed, the pre-amplifier and phase inverter stage 389, may, for example, be represented by a tube of the 6SC7 type functioning as a driver for the push-pull stages 385 and 387 although it is, of course, apparent that separate tubes connected to function as the single tube 389 may readily be substituted.

When the signals are impressed upon the input of both the second stage of the amplifier and inverter 389 and the input of one of the push-pull stages, those signals which were applied to the

phase inverter stage 389 are then supplied across the output resistor 399 and the coupling condenser to the grid or control electrode 403 of the other push-pull stage. Operating voltages for the anodes or plates of the pre-amplifier and phase inverter 389, as well as for the plates or anodes of the push-pull stages 385 and 387, are derived from the line 405 to which a source of positive voltage (not shown) has its positive terminal connected at the input 407 and its negative terminal (not shown) preferably grounded. The push-pull stages 385 and 387 thus derive voltages which are in push-pull with respect to each other and by virtue of the connection through the transformer 409 are caused to control the operation of the sound reproducer 120.

The deflection control for the image producing tube 100 is derived from the control or sync signals which are passed through the filter 107 consisting of the series inductance elements 411 and the shunt capacity elements 413 which are supplied to the separator stage 415. The signal which is supplied to the separator stage 415 from the output of the filter 107 and through the conductor 20 305 has the conventional wave form readily recognized for the standard video signal apart from the modifications mentioned. It has the sound sub-carrier removed by virtue of the sub-carrier filter 101. The triodes of the separator stage 415 function to perform the wave form separation of the sync signal so that at the point 417 which constitutes the output point of the first stage of the separator horizontal or line sync pulses are present whereas in the conductor 419 which leads from the output of the second half of the separator tube 415 the vertical sync pulses are present. The tube 415, in functioning as a relay and separator, has its operational time constant controlled largely by the combination of the condenser 421 and resistor 423. The condenser 421 couples the output of the first portion of the separator to the input of the second portion of the separator, with the adjustable grid leak resistor 423 serving to complete the control.

45 In the schematic showing of Fig. 2, the separator stage was conventionally represented at 109 and the horizontal deflection control 112 was shown as controlling the deflection produced by the horizontal deflection coils 104 and 105 while the vertical deflection control 113 controlled the deflection produced by the vertical deflection coils 102 and 103.

In the embodiment shown by Fig. 6 the tube 425 functions as the saw tooth wave generator (similar to element 113 of Fig. 2) for developing the vertical deflection saw tooth current. The general arrangement is such that the first half of the tube 425 functions essentially as the driver stage and the second half of the tube functions as the power stage. The arrangement provided is such that the anode or plate 427 in the first half of the tube is connected to the source (not shown) of positive voltage which connects at the terminal 429 and leads to the several tubes from the supply line 429'. The connection of the anode or plate 427 of the tube 425 to the supply line 429' is made by way of the transformer winding 431. Feedback between the plate and the grid circuit of this first half of the tube is provided by the transformer secondary winding 433 feeding back to supply suitable voltage to the grid or control electrode 435. The grid 435 is biased through a series of resistance elements 437 and a condenser 439 is connected between the grid and ground. Effectively, the transformer sec-

31

ondary winding 433 is between the grid and the junction of the resistor and condenser so that the combination forms a bridge circuit.

Depending upon the control to be effected, signals are then impressed upon the second half of the tube 425 by way of the time constant circuit comprising condenser 441 and resistor 443 so that in the output of the second half of the tube current amplification is produced and transferred by way of the transformer 445 to the line 447 connecting to the vertical deflecting coils.

Similarly, the horizontal and line frequency pulses which appear, as above stated, at the point 417 are supplied along the conductor 449 to energize the line deflection control circuit 112 formed to include preferably the coupling and horizontal driver stage tube 451 of which the first half of the tube, as shown, functions as the coupling stage and the second half functions as the horizontal driver stage. The horizontal driver stage is triggered in accordance with the cathode output of the first half of the tube as supplied to the driver stage through the coupling condenser 453 and across the cathode resistor 455 thereof. The driver stage 451, like the vertical driver stage hereinbefore explained, corresponds substantially to the form of deflection circuit control set forth by the co-pending application filed by this applicant on March 16, 1942, as Serial No. 434,805, now U. S. Patent No. 2,396,439, and entitled "Electron tube circuits."

In connection with the horizontal driver stage, the plate or anode 457 of tube 451 connects to the source of positive voltage in line 429 by way of the transformer primary 459. The grid or control electrode 461 connects to one terminal of the secondary winding 463 of the transformer. The other terminal of the transformer secondary winding 463 connects to the junction of the resistance combination 465 (preferably including the variable resistor 466 and the fixed resistor 467) and the storage condenser 469 so that the transformer secondary connected between these points and the grid serves to convert essentially the circuit into a bridge. With the application of the synchronizing impulses from the amplifier stage of tube 451 into the cathode circuit of the second half of tube 451, functioning as the driver stage there will be developed at point 471, and across condenser 469, a saw tooth voltage wave, as also explained in the aforementioned co-pending application. This saw tooth voltage pulse then is applied through the condenser 473 to the grid 475 of the power stage 477 (which preferably may be a tube of the 6L6 type). From the output of the tube 477 the resultant saw tooth currents at line frequency are supplied by way of the transformer 479 to the deflecting coils 104 and 105 to effect deflection in a horizontal path and at the same time to effect deflection by means of the same control signal on which the sub-carrier frequency modulated audio signals have initially been supplied.

Various ways and means to supply operating voltages to the cathode ray tube may be utilized and for purposes of reference only this arrangement has been diagrammatically shown, by way of the rectifier tube 481 receiving power from the transformer 483 of which the primary winding connects to input terminals 485 in turn connecting to the local source of power. Operating voltages for the various elements of the cathode ray tube have been shown as being supplied from a voltage divider 487 in well-known manner. Suit-

32

able filtering has been schematically represented by means of the filter 489.

While it has been shown herein that the produced signals representative of the audio modulation are applied, when suitably separated from the video and control signal, to the sound reproducing element 120 it, of course, will be apparent that these audio modulation signals, as aforesaid, may be of various types and character. If, for instance, the sound or audio signals as herein referred to happen to be signals known as facsimile signals from which facsimile records could be built up, then, of course, the sound reproducer 120 may be replaced by suitable printer bar control arrangements such as those already known in the art and which might be illustratively represented by the drive means shown for controlling a printer bar, as by Young re-issue patent, No. 20,152, or by the means shown for this general purpose by Koch patent, No. 2,319,139, dated May 11, 1943, or still further, it might be represented for electrolytic recording, for instance, as shown by Young patent, No. 2,215,806, all of which are cited merely illustratively.

Various modifications may be made in the system herein disclosed and therefore, it is to be understood that the arrangement represented is merely presented as illustrative of the system and method herein set forth.

Having now described the invention, what is claimed and what it is desired to secure by Letters Patent is the following:

1. In a communication system comprising means for producing intelligence signal modulations of one character, and means for producing an interrupted and interspersed control pulse signal series which repeat at a uniform rate as short duration control signal pulses occurring at one selected and predetermined signal amplitude, means for transmitting said intelligence signal modulations with said control pulse signal series; a system for multiplexing other intelligence signals which occur within a relatively low frequency range as compared to the first signals with the first form of intelligence signal modulations which comprises oscillator means for developing oscillations at a frequency which is high relative to the frequency of the regularly recurring control pulse signals, means for normally maintaining the oscillator means in a state of inoperativeness, means controlled by each regularly recurring control signal pulse for keying the oscillator means for generating oscillations which start from a condition of zero phase and amplitude and at a predetermined time subsequent to the time of commencement of the control pulse signal initiating the said oscillations, means for frequency modulating the developed oscillation frequency wave by the other said intelligence signals, means for restoring the oscillation producing means to an inoperative state at substantially the time of cessation of each control signal pulse of the character initiating the oscillations, means to combine additively the frequency modulated oscillations with the control signal pulses, means for multiplexing said combined signal with said first named intelligence signal modulations.

2. The system claimed in claim 1 comprising, in addition, frequency multiplier means connected intermediate the said modulator and combining means for multiplying the frequency of the said modulated sub-carrier while retaining the condition of initial zero phase and amplitude at the start of the oscillation series.

33

3. In a communication system comprising means for producing video signals, means for producing regularly recurring short duration control signals, means for transmitting the video signals in interspersed series representing selected scanning line traces which are separated by said control signals, said control blanking receiver operation during a fly-back period intermediate successive line traces and wherein the blanking control signals occur at an amplitude level representative of black in the video signal and wherein another series of control signal pulses is developed during the period of the first said pulses and extending in the direction of a video signal representative of black and located wholly within the ultra black region beyond black, a system for multiplexing additional intelligence signals of generally relatively low frequency modulation signals with the video signal modulations which comprises oscillator means for developing oscillations at a frequency which is high relative to the regularly recurring blanking control signals, means for normally maintaining the oscillator in an arrested state incapable of developing output oscillations, means controlled by each regularly recurring blanking control signal for supplying operating voltages to the oscillator to key it to an operative state with the commencement of each series of oscillations starting at zero phase and amplitude, means for frequency modulating the developed oscillation frequency wave by the additional intelligence signals, means removing the voltage supply to the oscillator under the control of the blanking pulses for damping the oscillator to an inoperative state at substantially the time of cessation of each control signal which caused initiation of oscillations so that the frequency modulated oscillations persist only during the fly-back period of the cycle intermediate successive scanning line traces, means to combine additively the frequency modulated oscillation energy wave with the control signal pulses and means for multiplexing said combined signal with said video signals.

4. The system claimed in claim 3 comprising, in addition, frequency multiplier means connected intermediate the said modulator and combining means for multiplying the frequency of said modulated sub-carrier while retaining the condition of initial zero phase and amplitude at the start of the oscillation series.

5. In a communication system comprising means for producing intelligence signal modulations of one character, means for producing recurring short duration control signal pulses, means whereby said intelligence signal modulations are transmitted as interrupted signal series with which the short duration control signal pulses are interspersed and wherein the control signal pulses are at one selected amplitude level, a system for multiplexing a second variety of intelligence signals with the first form of intelligence signal modulations which comprises oscillator means for developing oscillations at a frequency which is high relative to the frequency of the regularly recurring control pulse signals, means for normally maintaining the oscillator means in a state of inoperativeness, means controlled by each regularly recurring control signal pulse for keying the oscillation generating means to an operative state so that oscillating energy waves are developed with initial development of each wave series starting from zero amplitude and zero phase at the time of commencement of oscillations after each interruption, means for controlling the production of the said

34

oscillations so that each series of wave starts a predetermined time subsequent to the control pulse which initiates the oscillations, means for frequency modulating the developed oscillation frequency wave by the second variety of intelligence signals, means for restoring the oscillation producing means to an inoperative state at a predetermined time relative to the time of cessation of each control signal pulse which caused initiation of oscillations, means to supply both the frequency modulated oscillations and the control signal pulses to a load circuit in timed relationship coinciding with the development thereof, means for multiplexing said intelligence signal modulations of one character with said frequency modulated oscillations and the control signal pulses.

6. In a communication system comprising means for producing intelligence signal modulations of one character, means for producing recurring short duration control signal pulses, means whereby said intelligence signal modulations are transmitted as interrupted signal series with which the short duration control signal pulses are interspersed and wherein the control signal pulses are at one selected signal amplitude representative of one predetermined state of intelligence representation in the interrupted signal series, a system for multiplexing a second variety of intelligence signals which occur within a relatively low frequency range compared to the frequency of the first form of intelligence signal modulations which comprises means for developing oscillations at a frequency which is high relative to the frequency of the regularly recurring control pulse signals, means for normally maintaining the means to develop oscillations in a state of inoperativeness, means controlled by each regularly recurring control signal pulse for keying the means for generating oscillations so that oscillating energy waves are developed with each of the wave series starting in like phase at the time of commencement of oscillations after each interruption, means for frequency modulating the developed oscillation frequency wave by the second variety of intelligence signals, means for restoring the oscillation producing means to an inoperative state at substantially the time of cessation of each control signal pulse of the character causing initiation of oscillations, means to combine additively the frequency modulated oscillations with the control signal pulses, means for multiplexing said intelligence signal modulations of one character with said combined signal.

7. In a communication system comprising means for producing video signals, means for producing regularly recurring short duration control signals, means for transmitting the video signals in interspersed series which are separated by said control signals for blanking, synchronizing and synthesizing receiver operation and wherein one of the control signals is at an amplitude representative of black in the video signal and wherein another of the control signals is in the direction of a video signal representative of black and located wholly within a region beyond black, a system for multiplexing relatively low frequency modulation signals with the video signal modulations which comprises an oscillator for developing oscillations at a frequency which is high relative to one of the regularly recurring control signals, means for normally maintaining the oscillator in a state incapable of developing output oscillations, means controlled by each regularly recurring control signal of like control

characteristics for keying the oscillator to an operative state and in like phase at the time of commencement of oscillations after each interruption, means for frequency modulating the developed oscillation frequency wave by the relatively low frequency signals, means for damping the oscillator to an inoperative state at substantially the time of cessation of each control signal which caused initiation of oscillations, means to combine additively the frequency modulated oscillation energy wave with the control signal pulses and means for multiplexing the video signals and the combined frequency modulated oscillation energy wave and the control signal pulses.

8. In a communication system comprising means for producing video signal modulations, means for producing regularly recurring short duration control signal pulses, means for transmitting the video signal modulations as interrupted signal series which are separated by the control signal pulses, said control signal pulses serving at signal receiving points for synthesizing receiver operation and wherein each control signal pulse of like control characteristics occurs at a signal amplitude representative of one predetermined light and shadow representation in the video signal, a system for multiplexing relatively low frequency intelligence modulation signals with the video signal modulations which comprises an oscillator means for developing oscillation frequencies which are high relative to the frequency of recurrence of the control pulses, means controlled by each control pulse of like control characteristics for initiating oscillations in the oscillator means substantially with the commencement of the control pulse and for causing the oscillations always to commence in like phase, means for rendering the oscillation producing means inoperative with a cessation of the control pulse serving to initiate the oscillations and for holding the said oscillator means inoperative in the time interval between like character control signal pulses, means for frequency modulating the developed oscillations by the low frequency intelligence signals, means for additively combining the resultant frequency modulated oscillations with the control pulse signals which initiated the operation of the oscillation producing means, means for multiplexing said video signal modulations and said combined signal.

9. In a communication system comprising means for producing intelligence signal modulations, means for producing regularly recurring short duration control signal pulses, means whereby the intelligence signal modulations are transmitted as interrupted signal series with which the control pulses are interspersed and wherein the control signal pulses occur at a selected signal amplitude representative of one predetermined state of intelligence representations in the interrupted signal series, a system for multiplexing a second variety of intelligence signals which occur at relatively low frequency with the first form of intelligence signal modulations comprising means for developing oscillations at a frequency which is high relative to the recurrence frequency of the control pulse signals, means for normally maintaining the means to develop oscillations in a state of inoperativeness, means controlled by each regularly recurring like character control signal pulse for keying the means for generating oscillations so that oscillating energy waves are developed with each of the wave series starting in like phase at the time of commencement of oscillations after each interrupt-

tion, means for frequency modulating the developed oscillation frequency wave by the second variety of intelligence signals, means for restoring the oscillation producing means to an inoperative state at substantially the time of cessation of each control signal pulse of the character causing initiation of oscillations, means to combine additively the frequency modulated oscillations with the initially unmodulated control signal pulses and means for multiplexing said intelligence signal modulations and said combined signal.

10. In a communication system comprising means for producing television intelligence video signal modulations and means for producing regularly recurring short duration operation control signal pulses, means for producing sound intelligence signals, means for multiplexing said television intelligence video signal modulations which are initiated as regularly repeating interrupted signal series each interspersed with regularly recurring short duration video operation control signal pulses which each occur at a selected signal level representative of one predetermined state of light and shadow representation in the interrupted video signal series with sound intelligence signals which represent relatively low frequency ranges as compared with the video intelligence signal modulations, oscillator means for developing oscillations at a frequency which is high relative to the frequency of the regularly recurring control pulse signals, means for normally maintaining the oscillator means in a state of inoperativeness, means responsive to each regularly recurring control signal pulse for energizing the oscillator so that oscillating energy wave series are developed with each of the wave series starting in like phase at the time of commencement of each series of oscillations after each interruption, means for frequency modulating the developed oscillation frequency wave by the relatively low frequency sound intelligence signals, means for restoring the oscillator means to an inoperative state at substantially the time of cessation of each control signal pulse of the character causing initiation of oscillations, and means to combine additively the frequency modulated oscillations with the unmodulated control signal pulses.

11. In a communication system comprising means for producing video signals, means for producing short duration control signals, means for producing synchronizing signals, means for producing relatively low frequency modulation signals, means for transmitting the video signals in interspersed series which are interrupted and separated by the regularly recurring short duration control signals for blanking upon which pulses the synchronizing signals are superimposed for synthesizing receiver operation and wherein the blanking control signals is at a level representative of black in the video signal and wherein synchronizing signals all occur in the ultra black region and each synchronizing pulse is initiated with a predetermined delay following each blanking pulse, a system for multiplexing the relatively low frequency modulation signals with the video blanking and synchronizing signal modulations which comprises means, an oscillator connected so as normally to be inoperative to develop oscillations, a tank circuit for said oscillator, means controlled by one of the control signal pulses for deriving voltage pulses under the control of the blanking pulses and in the time period subsequent to the start of the synchronizing pulse, means to apply the said voltage pulses

to the oscillator in such manner that the pulses by-pass the oscillatory circuit while providing operating voltage for the oscillator so that a series of relatively high frequency oscillations result from the oscillator with each series of oscillations starting a zero amplitude and phase and each series occurring in the immediate post blanking pulse initiation series, means to limit the duration of the operating voltage pulses to a period of the order of the synchronizing pulse duration, means to arrest the oscillations of the oscillator with a cessation of the applied voltage pulses, means for frequency modulating the developed oscillation frequencies by relatively low frequency modulation signal energy, and means for additively combining the generated control pulses and the frequency modulated oscillator output with the video signals during the time of interruption thereof so that the resultant combined signal series is adapted for modulating a transmission channel in sequence by the plurality of control signals in such a way that the said signals are effective at receiving points in a manner substantially as if continuously developed.

12. The system claimed in claim 11 comprising, in addition, frequency multiplier means connected intermediate the said modulator and combining means for multiplying the frequency of said modulated sub-carrier while retaining the condition of initial zero phase and amplitude at the start of the oscillation series.

13. In a communication system comprising means for generating regularly recurring control pulses and intelligence signal trains and wherein all of the said control signal pulses are developed at a signal level of predetermined and substantially fixed amplitude, a system for multiplexing a plurality of modulation signals which comprises an oscillator having a tank circuit wherein oscillations are developed at a frequency which is relatively high compared to the recurrence frequency of the control signal pulses, means to derive voltage pulses from the said control pulses, means to supply the said voltage pulse to the oscillator at predetermined time periods following each pulse to cause the oscillations to be developed in the tank circuit while the said pulses are confined externally of the tank circuit, the said oscillations being started in each instance from a zero amplitude and phase condition, each developed oscillation frequency wave burst by one of the modulating signals, means for quenching oscillations in the oscillator at times of cessation of each voltage pulse which initiated the oscillations, means additively to combine the frequency modulated oscillating energy wave with the control signal pulses in time relationship coinciding with the initial time sequence of control pulses and oscillations, means for multiplexing the intelligence signal trains and the additively combined signals for transmission.

14. The system claimed in claim 13 comprising, in addition, frequency multiplier means connected intermediate the said modulator and combining means for multiplying the frequency of said modulated sub-carrier while retaining the condition of initial zero phase and amplitude at the start of the oscillation series.

15. In a communication system comprising means for generating video signals, means for generating regularly recurring short duration control signal pulses and means for developing relatively low frequency modulation signals, means for transmitting the video signals in interspersed series to represent different traced paths of an image area with the several series separated

5 by regularly recurring short duration control signal pulses and a predetermined group of video and short duration control signals are followed by longer duration pulses and the two forms of pulses are useable at receiver points for synchronizing and synthesizing the receiver operation with the transmitter and wherein the control signal pulses are developed at a signal level which is effective in signal receivers as a signal wholly within a region beyond black in the image causing the video signal, a system for multiplexing relatively low frequency modulation signals with the video signal modulations which comprises an oscillator having a tank circuit wherein oscillation frequencies which are a predetermined multiple of the recurrence frequency of the control signal pulses are developed, means responsive to each control pulse of like control characteristics and completely separate from the tank circuit for initiating oscillations which start from zero amplitude and phase in the said oscillator means substantially within a predetermined time following the commencement of the control signal pulse by providing the said pulses as the power supply for the oscillator, means for arresting the operation of the oscillator means so that its output reaches a zero value with a cessation of the power supply persisting only during each control pulse and serving to initiate the oscillations, means for frequency modulating the developed sub-carrier oscillations the low frequency signals in such a manner that the developed center frequency is a multiple of the recurrence frequency of the control signal pulses, means for additively combining the frequency modulated sub-carrier signal energy with the control signal pulses which initiate the oscillations, means for multiplexing the video signal modulations with the additive signal.

16. The system claimed in claim 15 comprising, in addition, frequency multiplier means connected intermediate the said modulator and combining means for multiplying the frequency of said modulated sub-carrier while retaining the condition of initial zero phase and amplitude at the start of the oscillation series.

17. In a communication system comprising means for producing video signals, means for producing sets of control signals, means for producing relatively low frequency modulation signals, means for transmitting the video signals in interspersed series which are interrupted and separated by the regularly recurring short duration control signals for blanking, synchronizing and synthesizing receiver operation and wherein one of the control signals is at a level representative of black in the video signal and wherein another of the control signals is in the direction of a video signal representative of black and located wholly within a region beyond black, a system for multiplexing relatively low frequency modulation signals with the video signal modulations which comprises means for developing trains of video signal series interrupted for short time durations relative to the period of video signal duration following each signal series to provide for the transmission of the said control signals for synthesizing receiver operation, means for developing control signal pulses which are initiated during interruption periods of the video signal modulations, an oscillator unit normally arranged to be inoperative to develop oscillations, means controlled by one of the control signal pulses for initiating a series of relatively high frequency oscillations from the oscillator with each series of oscillations starting in like phase and each series

occurring during the periods of development of each like character control pulse and for a duration substantially coinciding with the duration period of the said control pulse, means for frequency modulating the developed oscillation frequencies by relatively low frequency modulation signal energy, and means for additively combining the generated control pulses and the frequency modulated oscillator output with the video signals during the time of interruption thereof so that the resultant combined signal series is adapted for modulating a transmission channel in sequence by the plurality of control signals in such a way that the said signals are effective at receiving points in a manner substantially as if continuously developed.
